(21) Appl. No.: **29/251,290**

(57) **CLAIM**

(22) Filed: **Jan. 5, 2006**

We claim the ornamental design for the pair of weight arm assemblies for an exercise apparatus, as shown and described.

(51) **LOC (8) Cl.** 21-02

DESCRIPTION

(52) **U.S. Cl.** **D21/694**

FIG. 1 is a perspective view of a pair of weight arm assemblies for an exercise apparatus showing our new design;

(58) **Field of Classification Search** D21/662,

FIG. 2 is a perspective view of the right hand weight arm assembly;

D21/674, 675, 676, 694; 482/95, 96, 97,

FIG. 3 is an outside side view of the right hand weight arm assembly;

482/104, 129, 130, 136, 137, 138, 133, 98,

482/142

FIG. 4 is a front view of the right hand weight arm assembly;

See application file for complete search history.

FIG. 5 is a rear view of the right hand weight arm assembly.
